UNITED STATES PATENT OFFICE.

EDDY ISHAM WEST AND LE ROY DANIEL WEST, OF OAKLAND, CALIFORNIA, AS-SIGNORS OF FIFTY-ONE PER CENT TO WILLIAM H. RAPLEE, OF OAKLAND, CALIFORNIA.

CENTRIFUGAL SEPARATOR.

Application filed July 12, 1923. Serial No. 651,017.

To all whom it may concern:

Be it known that we, EDDY ISHAM WEST and LE ROY DANIEL WEST, citizens of the United States, residing at Oakland, county 5 of Alameda, and State of California, have invented new and useful Improvements in Centrifugal Separators, of which the following is a specification.

This invention relates to a process and 10 apparatus for recovering precious metals by amalgamation.

It is the object of the present invention to provide an improved apparatus of the character referred to, by the use of which a 15 maximum recovery of the precious metal contents of ore pump and metal bearing sands may be economically effected.

In carrying out this object, the pulp or sand is passed through a rotating cylinder, 20 the interior surface of which carries a wall of fluid mercury for gathering the particles of precious metals carried in the gangue and for separating them therefrom during the flow of the gangue through the cylinder.

25 The rotating cylinder is preferably disposed on the horizontal, and its rotation causes the heavier particles of material to be thrown by centrifugal action outwardly against the wall of mercury while the 30 gangue is being passed through the cylinder under pressure of its hydrostatic head and suction created at the discharge end of the cylinder.

The preferred form of apparatus for 35 practicing my invention is illustrated in the accompanying drawings in which:

Fig. 1 is a longitudinal central section through the apparatus.

Fig. 2 is an end elevation of the same.

40 Fig. 3 is a transverse section taken on line 3—3 of Fig. 1.

Referring more particularly to the accompanying drawings, 10 indicates a hollow cylinder, the end 11 of which is reduced in 45 diameter and constitutes a trunnion, which is journalled in a bearing 12. The other end of the cylinder threadedly connects with a bell shaped head member 14 which is formed with a reduced end 15 constituting 50 a trunnion. This trunnion is journalled in a bearing 16 and is fitted with a pulley 15a by which the structure may be rapidly 55 revolved. The reduced end 11 of the cylinder is centrally bored and constitutes a communicating passageway between the interior

of the cylinder and a feed hopper 17. This hopper is supported by the bearing 12 as shown in Fig. 1.

The interior of the cylinder is formed with a plurality of annular ruffles 18 spaced equal distances apart forming annular pockets 19 therebetween. The interior diameter of the ruffles gradually increases from the feed end to the discharge end of the cylinder as is clearly illustrated in Fig. 60 1. Adjacent the discharge end of the cylinder, the head member 14 is formed with a plurality of radially disposed discharge ports 20, which communicate with a stationary pump casing 21. This casing is channel 70 shaped in cross section, as shown in Fig. 1, and surrounds an enlarged portion 22 formed on the head member 14 through which the discharge ports 20 are formed. The pump casing is fitted with a discharge 75 nozzle 23 which may be connected by pipes to a tank into which the tailings may be deposited.

In operation, sufficient mercury is introduced into the cylinder to permit a wall of 80 mercury to be formed by centrifugal action over the interior of the cylinder when the latter is revolved. The pulp or slime is fed into the machine through the feed hopper 17. Immediately after the pulp enters 85 the cylinder it is subjected to the centrifugal action thereof and the particles of precious metal are thereby projected into the wall of mercury, while the gangue passes through the cylinder and discharges through the 90 ports 20.

As the cylinder revolves rapidly, the tailings discharging through the ports 20 into the pump casing will be discharged through the nozzle 23 of the pump. This action 95 will create a suction in the cylinder to assist the feeding of the pulp therethrough.

It is obvious that when the pulp is passed over the wall of mercury, the centrifugal action will project the metal particles there-in into the wall and cause them to accumulate in the pockets between the ruffles. Access may be had to the interior of the cylinder for cleaning purposes by removing the head member 14.

100 By forming the opposite ends of the cylinder with heads having trunnions which rotatably support the same and by feeding the pulp through one of the trunnions and heads, we prevent the pulp from reaching 110

and destroying the bearings. This adds greatly to the efficiency of the device.

From the foregoing it is obvious that an improved process and apparatus for recovering precious metal from ore pulp has been provided. While we have shown and described the invention as now known to us, we wish it understood that various changes in the apparatus may be resorted to without departing from the invention as defined in the appended claims.

Having thus described our invention, what we claim and desire to secure by Letters Patent is:—

15. 1. A machine for the recovery of precious metals comprising a horizontally disposed hollow barrel having annular riffles formed around its interior surface, one end of said barrel being reduced in diameter, a bearing in which said reduced end is journalled, a feed hopper associated with said barrel, said reduced end being centrally bored whereby to provide a communicating passageway between said feed hopper and the interior of the barrel, a hollow head member connected to the barrel at the other end thereof to close the same, one end of said head member being reduced in diameter, a bearing in which the reduced end of said head member is journalled, a plurality of radially disposed ports formed around the circumference of the head member adjacent the end of the barrel, and a stationary pump casing surrounding said head member and enclosing said ports whereby when said barrel is rotated the material entering the barrel through the feed hopper will be drawn through said ports and discharged from said pump casing.
20. 2. A machine for the recovery of precious metals comprising a horizontally disposed hollow barrel, one end of said barrel being reduced in diameter, a bearing in which said reduced end of the barrel is journalled, a feed hopper associated with said barrel, said reduced end of the barrel being bored to provide a communicating passageway between said hopper and the interior of the barrel the interior of the barrel being formed with a plurality of annular pockets for containing an amalgamating agent, a hollow head member threaded on the other end of said barrel for closing the same, said head member being formed with an end of reduced diameter, a bearing in which said reduced end of the head member is journalled, said head member being formed with an annular enlargement adjacent the point where it joins the end of the

barrel, a plurality of radial ports extending through said head member around the circumference of the enlargement, a stationary pump casing surrounding the said enlargement on the head member whereby when said barrel is revolved the material fed into the barrel from the feed hopper will be drawn through the barrel and discharged from the pump casing.

3. A machine for the recovery of precious metals comprising a horizontally disposed cylindrical shell having riffles formed around its interior surface, heads at opposite ends of the shell, a trunnion carried by each head, bearings in which said trunnions are journalled for rotatably supporting the shell, a feed hopper associated with the shell, the trunnion and head at one end of the shell having a passageway formed therethrough to provide communication between said feed hopper and the interior of the barrel, a plurality of radially disposed ports formed around the circumference of the shell adjacent the opposite head, and a stationary pump casing surrounding the shell and enclosing said ports whereby when said shell is rotated material entering the shell through said passageway will be drawn through said ports and discharged from the pump casing.

4. A machine for the recovery of precious metals comprising a horizontally disposed cylindrical shell, the same having a counterform interior bore formed with a plurality of annular pockets adapted to contain an amalgamating agent, heads at opposite ends of the shell, trunnions projecting from the heads, bearings in which trunnions are journalled for rotatably supporting the shell, a feed hopper associated with the shell, the trunnion and head at one end of the barrel being bored to provide a communicating passageway between said hopper and the interior of the shell, the opposite head being closed and detachably connected to the shell, the said bored head being concave whereby material entering through said passageway will be directed to the counterform interior surface of the shell, a plurality of radial ports formed through said shell adjacent the closed head, and a stationary pump casing surrounding the shell and enclosing said ports whereby when said shell is revolved the material fed into the shell through said passageway will be drawn through the shell and discharged from the pump casing.

EDDY ISHAM WEST.
LE ROY DANIEL WEST.
